UNITED STATES PATENT OFFICE.

SEBASTIANO G. BARTOLOTTA, OF MIDDLETOWN, CONNECTICUT, ASSIGNOR OF ONE-HALF TO DOMINICK CAMBRIA AND CARL F. ANDERSON, BOTH OF MIDDLETOWN, CONNECTICUT.

LOOM.

Application filed March 10, 1927. Serial No. 174,233.

This invention relates to looms, and particularly to looms for weaving relatively narrow fabrics, especially straps, brake lining, belts, ribbon and so forth.

At the present time it is common practice in weaving this type of article to throw the shuttle carrying the bobbin back and forth through the open shed to form the weft or filling, but it will be obvious that in this type of machine the supply of filling thread which may be carried by the shuttle is limited, and therefore, is exhausted in a short time requiring the stopping of the loom until it can be replenished. The time consumed for this purpose is a considerable portion of the time available, thus cutting down production. To overcome these objections looms have been devised which employ a reciprocating needle for laying the filling thread in relatively narrow fabrics, but these devices have been complicated and have required special loom constructions which necessitate practically a new loom or practically an entire rebuilding of the old loom. I have devised a construction which may be applied to the standard loom constructions and employs a reciprocating needle for laying the filling or weft thread so that this thread may be taken from a supply sufficiently large to last for a day's run or even longer, and which mechanism is mounted on the standard lay and is operated by the mechanism associated therewith.

Referring to the accompanying drawings, Fig. 1 is a front elevation of the upper portion of a lay with my improved device applied thereto, a portion of the shed mechanism being also shown.

Fig. 2 is a similar view of a portion of this mechanism in an intermediate position.

Fig. 3 is a similar view showing the mechanism in the other extreme position from Fig. 1.

Fig. 4 is a central longitudinal horizontal section, and

Fig. 5 is a vertical transverse section substantially on line 5—5 of Fig. 3.

The top horizontal beam of the lay is indicated at 10, mounted on the usual lay swords 11 to swing back and forth in the usual manner and by the usual mechanism, not shown, to beat the filling by means of the reed 12. The warp threads for a certain strip of fabric are indicated at 13 passing

through suitable guides 14 of the harness 15 by which the alternate threads are alternately raised and lowered to open the shed in a manner well known.

I have mounted my improved filling mechanism on this top beam 10 of the lay and it, therefore, moves with the lay, and it is operated by the usual mechanism (not shown) employed to throw the shuttle back and forth along the raceway on the top of the lay. This device comprises several units 60 as shown on the drawing, there being a unit for each belt or strip woven and, of course, the number of units or the number of strips which may be woven at the same time on the loom will depend on the length of the lay, 70 and therefore, the space available. Each unit comprises a block 16 mounted on the lay and having a curved guideway 17 for a shuttle 18 carrying a bobbin 19. The center of the block may comprise semi-circular plates 20 having a peripheral flange 21 under which one side of the shuttle is guided to retain it in the guideway, and the other side may be guided under overhanging plates 22 and 23. The block and shuttle 80 guide are located at one side of the warp threads 13 for a single strip, and on the opposite side is located a device for laying the weft or filling thread in the warp. This device comprises a guide or needle 24 having an eye 25 at its free end for passing of the filling thread 26, and adjacent its other end is provided with an eye 27 to which the thread leads from a suitable guide and tension device 28, and to the 90 tension device from the supply spool 29. The needle is mounted on a reciprocating bar 30 by means of an upright support 31, and the connection between the needle and this support passes through an elongated slot 32 in the block for the next unit so that the support 31 and the needle bar 30 are located at the rear side of the block. The needle bar is operated by means of a frame 33 mounted to reciprocate longitudinally of the lay and having a rack 34 meshing with a gear 35 carrying an arm 36 connected by means of a link 37 with the needle bar, so that as the frame is reciprocated the gear is rotated to reciprocate the 95 needle bar and the needles carried thereby in certain timed relation with the movements of the shuttles. It will be noted that the 100 105

rack 34 has a gap 38 which is so located and of a proper length to allow the needles to remain stationary for a certain length of time during the movement of the frame as will later be described.

Suitable mechanism is provided for moving the shuttle 18 back and forth in its guideway in certain timed relation with the movements of the needle. This is done by gear mechanisms associated with the rack 34 and another rack 39 at the top of the frame. One side of the shuttle is provided with a rack 40, and while in the lower portion of its guideway it meshes with a gear 41 meshing with a second gear 42 which meshes with the rack 34. While in the upper portion of its guideway the rack on the shuttle meshes with a gear 43 meshing with an idler 44 meshing with a third gear 45 which also meshes with the upper rack 39. It will, therefore, be apparent that as the frame 33 is reciprocated it will also reciprocate the racks 34 and 39 which in turn will rotate the gears and swing the shuttle up and down across the horizontal center line, or the path of movement of the needle 24. As the shuttle moves upwardly the upper gear 43 will engage the rack thereon before the lower gear 41 releases the shuttle so that the shuttle is always in driving engagement with either the gear 41 or the gear 43. The frame 33 is reciprocated in certain timed relation with the operation of the shedding mechanism by the usual shuttle operating mechanism (not shown) associated with the lay, that is, this frame may be connected to this mechanism to be reciprocated thereby through the connections 46.

The operation is as follows: The shedding mechanism is operated to open the shed, as indicated in Fig. 5, in the usual manner, and the warp for all of the plurality of strips to be woven may, of course, be simultaneously operated by the same shedding mechanism. After the shed is open, if the parts are in the position of Fig. 1 the frame 33 is then moved to the right, as viewed in this figure. This movement will cause a half revolution of the gear 35 by the rack 34 at which time the gear will run into the gap 38 of this rack. This partial revolution of the gear 35 will shift the needle bar 30 and the needles 24 carried thereby to the extreme advanced or left hand position, as shown in Fig. 2, that is, with this needle extending through the separated warp threads so that its free end carrying the eye 25 is at the opposite side of the warp. It will be obvious that during this movement the needle will carry the filling thread 26 through the open shed between the separated warps, as indicated in Fig. 2. During this movement of the needle the gears 41 and 42 have been moving the shuttle 18 upwardly or counterclockwise in its guideway, as viewed in Fig. 1, but the

gears are so proportioned that the needle is in the position of Fig. 2 before the upper end of the shuttle reaches the path of movement of the needle. The needle then remains stationary, because of the gap 38 in the rack 34, while continued movement of the frame 33 will cause the shuttle to pass up between the filling thread 26 and the needle, as indicated in Fig. 2. After the shuttle has passed by the needle, further continued movement of the frame 33 to the right will cause the rack 34 to again engage the gear 35 and give it another half revolution. This last half revolution will shift the needle bar 30 and the needles 24 carried thereby to the right and back to their original position, as indicated in Fig. 3, but the frame 33 will be in its extreme right hand position. From an inspection of Fig. 3 it will be seen that the shuttle 18 is now in the upper part of its guideway and will mesh with the gear 43. It will be apparent that, as the shuttle was during this operation passed through the loop formed by the filling thread 26 at the free end of the needle, it carried the bobbin thread 47 through this loop, and therefore, when the needle was again retracted from the position of Fig. 2 to withdraw it from the warp, the filling thread was held by the bobbin thread 47, as indicated in Figs. 3 and 4.

The shedding mechanism is now shifted to move the warp threads by each other to again open the warp in the opposite direction, after which the frame 33 is shifted back to the left or the original position of Fig. 1. During this backward movement the free end of the needle is again passed through the open shed, the needle remaining stationary because of the gap 38 in the rack 34 while the shuttle is passed downwardly through the loop in the filling thread at the end of the needle, and the needle is again retracted to its original position, Fig. 1. Therefore, at each time the frame 33 is shifted in either direction two filling threads are laid in the warp, and it is held at one edge by the bobbin thread 47. Therefore, in effect the shuttle merely lays an additional warp thread along one edge of the strip being woven. It is, therefore, able to carry sufficient thread for a very long strip, and as the supply 29 may be any size desired the loom may operate for a long time without requiring replenishing of the thread, and therefore, the time lost in stoppage of the loom for this purpose is reduced to a minimum.

It is to be noted from Figs. 1, 2 and 3 that the needle for weaving one strip may be mounted in the slot 32 in the block carrying the next adjacent shuttle, so that the space required for each individual strip weaving means is reduced to a minimum. It will also be noted that the needle and shuttle

mechanism for all the plurality of strips is mounted on the lay and moves therewith, and may be operated from the shuttle operating mechanism on the lay, so that this device may be applied to looms already installed.

5. Having thus set forth the nature of my invention, what I claim is:

1. In a loom the combination with means for holding and operating the warp including means for shedding the warp, and a movable lay, of a weft laying needle mounted to reciprocate on the lay through the shed of the warp, a block mounted on the lay provided with a guideway, a shuttle mounted in said guideway for reciprocating movement across the path of movement of the needle and having a rack, gears mounted on opposite sides of the needle path and adapted to mesh with said rack, and a frame mounted to reciprocate on said lay and including spaced racks meshing respectively with the gears on opposite sides of the needle path.

2. In a loom the combination with means for holding the warp, means for shedding the warp and a movable lay, of a weft laying needle mounted on the lay and adapted to reciprocate through the shed of the warp, a support mounted on the lay having a guideway, a movable shuttle mounted in said guideway provided with a rack, gears on opposite sides of the needle path adapted to mesh with said rack, and means on the lay for operating the needle and the shuttle in certain timed relation with the shedding mechanism comprising a frame mounted to reciprocate on the lay including racks meshing respectively with the gears on opposite sides of the needle path and means connected to said frame for reciprocating the needle.

3. In a loom the combination with means for holding the warp, means for shedding the warp and a movable lay, of a weft laying needle mounted on the lay and adapted to reciprocate through the shed of the warp, a support mounted on the lay on the opposite side of the warp from the needle and having a guideway, a shuttle mounted in said guideway, a longitudinally reciprocable frame on the lay, means operated by said frame for reciprocating the needle and the shuttle, and means for reciprocating said frame in certain timed relation with the shedding mechanism.

4. In a loom the combination with means for holding the warp, means for shedding the warp and a movable lay, of a weft laying needle mounted on the lay and adapted to reciprocate through the shed of the warp, a support mounted on the lay on the opposite side of the warp from the needle and having a guideway, a shuttle mounted in said guideway, reciprocable racks mounted on the lay, gears meshing with the racks, means operated by the gears for reciprocating the needle and the shuttle, and means

for reciprocating the racks in certain timed relation with the operation of the shedding mechanism.

5. In a loom the combination with means for holding and operating the warp including means for shedding the warp, and a movable lay, of a weft laying needle mounted to reciprocate on the lay through the shed of the warp, a block mounted on the lay provided with a guideway, a shuttle mounted in said guideway for reciprocating movement across the path of movement of the needle, said shuttle having a rack in one side thereof, gears in the block on opposite sides of the needle path and adapted to mesh with said rack, a frame mounted to reciprocate longitudinally of the lay, racks carried by the frame having driving connection with the said gears, means operated by the frame for reciprocating the needle, and means for reciprocating the frame in certain timed relation with the operation of the shedding mechanism.

6. In a loom the combination with means for holding the warp, means for shedding the warp and a movable lay, of a weft laying needle mounted on the lay and adapted to reciprocate through the shed of the warp, a shuttle mounted to move back and forth across the path of the needle, a gear having driving connection with the needle for reciprocating the same, a frame mounted to reciprocate on the lay, a rack carried by the frame meshing with said gear and having a gap to permit the needle to remain stationary for a portion of the movement of the frame, and driving connection from the frame to the shuttle.

7. In a loom the combination with means for holding the warp and means for shedding the warp, of a weft laying needle mounted on one side of the warp and adapted to reciprocate through the shed of the warp, a support mounted on the other side of the shed and having a guideway, a shuttle mounted to reciprocate in said guideway across the path of movement of the needle, a reciprocable frame, and driving connections from the frame to the needle and the shuttle.

8. In a loom the combination of a plurality of spaced warp sheds, means for shedding the warps, supports mounted between the sheds and having guideways, a weft laying needle mounted to reciprocate across each shed, shuttles mounted in the guideways and adapted to reciprocate across the paths of movement of the needles, a reciprocating bar connected to the needles, a reciprocating frame, and driving connections from the frame to said bar and from the frame to the shuttles.

9. In a loom the combination of a plurality of spaced warp sheds, means for shedding the warps, supports mounted between

the sheds and each having a longitudinal slot and a curved guideway extending on opposite sides of said slot, shuttles mounted to reciprocate in said guideways, weft laying needles in said slots and each adapted to reciprocate across a shed, a reciprocating bar connected to the needles, a reciprocating frame having a pair of racks, a gear mesh-

ing with one of said racks and connected to said bar, gear connections between the racks and the shuttles, and means for reciprocating the frame in certain timed relation with the warp shedding means. ¹⁰

In testimony whereof I affix my signature.

SEBASTIANO G. BARTOLOTTA.
